UNITED STATES PATENT OFFICE

FREDERICK K. FILDES, OF ALTOONA, PENNSYLVANIA

ATTACHMENT FOR CONTAINER CARRIERS

Application filed February 9, 1931. Serial No. 514,467.

This invention relates to container carriers for the transportation of bulk units such, for example, as the less-than-car-load units of the so-called container car service involving use of steel enclosures which are carried from place to place either upon specially equipped railroad cars, or motor trucks and trailers.

More particularly the present improvements have reference to an attachment for carriers adapted to the transportation of castor-equipped merchandise containers, which may be rolled from a platform or other suitable structure onto, or off, the carrier as and when required.

The primary object of this invention is to provide an attachment for flat carriers comprising co-active stationary and movable means to respectively prevent longitudinal and lateral shifting of a castor-equipped container, relative to the carrier during transportation, the means restraining transverse movement having capacity for limited angular inclination away from said container when the latter is to be raised or lowered from over-head, and fall-down pivotal action if the container be rolled-off or onto the carrier.

Another object is to provide an attachment of the typified character which is simple in construction, effective for the purposes had in view, and comparatively cheap to manufacture and install.

With the foregoing and other objects in view as will be hereinafter apparent, this invention consists in general of certain novel details of construction and combinations of parts fully set forth herein, illustrated by the accompanying drawings, and specifically claimed.

In the drawings:

Fig. I is a part side elevation of a railroad flat car equipped with attachments embodying the present improvements.

Fig. II is an end elevation looking toward the left hand of the preceding illustration.

Fig. III is a broken top plan view of a single attachment, on a somewhat larger scale.

Fig. IV is an end view of the same.

Fig. V is a perspective view of a stationary bearing member hereinafter fully described.

Fig. VI is a perspective view of a hinged component of the attachment effective in use to prevent lateral shifting of the container.

Fig. VII is a perspective view of a bolt supporting element; and,

Fig. VIII is a similar view of the bolt nut.

Referring more in detail to the drawings, the numeral 1 designates a portion of a railroad flat car, 2 the wheels, and 3 the supporting platform or floor.

In accordance with this invention, I mount at intervals transversely of the car floor 3 a series of attachments comprehensively designated 4, and in view of each such unit being alike, the following description is limited to one only, with corresponding reference indicia applied to the others, to avoid repetitive matter.

The attachment 4 comprises duplicate end members 5 for appropriate fixture to the side 70 sills 6 of the car 1, as by bolts or rivets 7. Each end member or stationary bracket 5, as best seen in Figs. III-V, embodies an attaching angle-section base 8, having laterally-projecting apertured ears 9, with vertical walls 10 united by an intervening web 11 and aligned buttress portions 12. At the upper ends the walls 10 have projections 13 affording attachment, as by rivets 14, for paralleling retainer members 15; also rigidly secured together in their mid-region by spatially-arranged U-shaped or channel-section partition element 16. Each channel section partition element 16 is provided with an elongated or substantially elliptical hole 17 in the web thereof, and they are suitably secured in permanent engagement between the retainer members 15, as by rivets 18, thereby materially reinforcing the attachment structure as a whole, while the holes 17 serve for a purpose later explained.

Hinged to the aforesaid apertured ears 9 of each stationary bracket 5 by an appropriate pivot pin or bolt 19 is a movement-restraining member 20 illustrated in perspective in Fig. VI. This hinged member 20, it will be seen from the view just referred to, comprises a body portion 21, of somewhat rectangular contour, with apertured offsets 22 at the lower edge whereby it is hinged

to the ears 9 by the pivot pin 19. The hinged member 20 is also formed with upper and lower reinforcing flanges 23, 24, respectively, connected by vertical buttress brackets 25; 5 while the body portion 21 is vertically outset somewhat at 26 and provided with a key-hole orifice 27, and at the upper part with a lateral projection 28, as well as spaced outwardly-inclined ears or guides 29, for purposes 10 later on set forth.

Retention of each hinged member 20 in operative relation with respect to the attachment 4 is effected by an associated bolt 30 passed outwardly through the elliptical hole

15 17 of the nearer partition element 16 and the key-hole slot 27 in said member. This bolt 30, it is to be noted, has a square head 31, fitting freely between the attachment retaining members 15; while said bolt is screw-

20 threaded at the outer end for reception of specially formed nut 32; while the bolt head 31 is chamfered at 33, and the pair involved in the attachment 4 are reversely placed with respect to such chamferings, for a reason

25 later on explained.

Each nut 32 is at a contour conformative to the key-hole slot 27, and when moved into registration therewith, beyond the province of normally coactive stop projections 34 on 30 the hinged member 20, permits said hinged member to be moved thereover; while the nut 32 is provided with a manipulator 35.

Having explained the structural features of the invention, it will be readily seen that

35 as each container 36 is moved into position on the car floor 3, between a pair of the attachments 4, that it will be held against longitudinal shifting, relative to the car 1, by engagement between the retaining members

40 15 of said attachments. The hinged members 20 are thereupon swung upwardly and the nuts 32 on the bolts 30 passed through the key-hole slots 27 in the body portions 21 of said members; such passage being effected by

45 rocking the bolts 30 vertically on the partition elements 16 as fulcrums, and as conventionally indicated by dot-and-dash lines at the left hand of Fig. II. Incidentally, the chamfer portions 33 of the bolts 30, and the 50 elongated holes 17 in the partition 16, accommodate such movement, while disposition of the heads 31 thereof in reverse position, as shown, permits placement of the partition elements nearer to the center of the retainer

55 members 15, thereby better reinforcing the attachment 4 where essential, as well as reducing the movement of the nuts 32 vertically to a minimum for purposes of engagement with and release from the hinged members 20.

60 Obviously the container 36 when moved, as just described, from a platform, or other surface, onto the car 1, is rolled on the castors 37 over a suitable gangway (not shown) intervening such platform and the car; while it is

65 further to be remarked that it is only neces-

sary to disengage the hinged members 20 from the bolts 30 on that side of the car 1 adjoining the platform. On the other hand, if the container 36 be lowered onto the car floor 3, by appropriate power-actuated tackle applied from above to the links 38 at the top of said container, it is only needful to slightly move the hinged members 20 outwardly from the vertical in order to assemble said container on the floor 3. Attention is here again drawn to provision of the inclined ears 29 on the hinged members 20 which serve to guide the container 36 into place transversely of the car 1 when lowered thereonto, as just referred to. Under either of the methods referred to of assembling the containers 36 on the car 1, it will be readily appreciated that, after said containers are placed in position, the nuts 32 are tightened up by aid of their respective manipulators 35 until the lateral projections 28, on the hinged members 20, abut against the side walls of the container 36 and thereby retain it against transverse shifting. The stop projections 34 cooperating with the associated nut 32, effectively prevent the bolt 30 from movement upwardly, whereby the hinged member might become released, incident to inadvertence in properly tightening up the nuts, or to excessive vibration during transportation tending to loosen said nuts.

When it is desired to remove a container 36 from the car 1, the nuts 32 are loosened, and the bolts 30 raised until the hinged members 20 are in position whereby said nuts are enabled to pass the key-hole slots 27, in the manner hereinbefore explained. The container 36 is thereupon freed for removal from the car 1 to a stationary platform or wherever desired; while it is noteworthy that the nuts 32 are, preferably, permanently-retained on the bolts 30, as by aid of cotter-pins 39, whereby losses are prevented and labor saved.

From the foregoing it will be understood this invention is susceptible of other adaptations, and embodiments in forms other than that which is illustrated by the attached drawings; hence I, therefore, consider as my own all such modifications thereof as fairly come within reasonable scope accorded the following claims.

Having thus described the invention, what I claim is:—

1. The combination with a container carrier of paralleling transverse barrier attachments affording longitudinal movement-restraint for the container, hinged members at the ends of the barrier attachments adapted for abutment with the container sides, and means having fulcrum support to each side of the carrier longitudinal center for clamping the hinged members in container abutting position, said means having capacity for angular-movement vertically for coaction with and release from the hinged members.

2. The combination with a container carrier of paralleling barrier attachments affording longitudinal movement-restraint for the container, members hinged at the ends of the attachments for abutment with the container sides to prevent lateral shifting, bolts for clamping the hinged members in container abutting position, and means permitting said bolts a limited degree of angular-movement vertically to secure and release the hinged members. 70
3. The combination with a container carrier of paralleling barrier attachments affording longitudinal movement-restraint for the container, members hinged at the ends of the attachments for abutment with the container sides to prevent lateral shifting, bolts for clamping the hinged members in container abutting position, means permitting said bolts a limited degree of angular-movement vertically to secure and release the hinged members, and means on the hinged members serving to prevent release of the aforesaid bolts when clamping said members against the container sides. 80
4. The combination with a carrier for a multiplicity of less-than-carrier-capacity containers of a sequence of paralleling barrier attachments effective to restrain longitudinal-movement of said containers, members hinged at the ends of each attachment having key-hole slots therein, clamp bolts having fulcrum support in the barrier portion of the attachments and projecting through the key-hole slots, and special nuts adapted for passage through the said slots and co-action with the hinged members to clamp the latter against the container sides or to sustain the same relatively released therefrom. 90
5. An attachment for flat carriers comprising a stationary barrier, members hinged at the ends of said barrier, and clamping means having fulcrum support in and approximate the center of the barrier for co-action with the hinged members to secure the same vertically. 100
6. An attachment for flat carriers comprising a stationary barrier, members hinged at the ends of said barrier with slots at right angles to their axes of movement, clamp bolts having their head ends afforded fulcrum support in the barrier with the threaded ends through the slots aforesaid, and nuts adapted for passage through said slots and coaction with the hinged members to secure the latter in active position or support them when inactive. 110
7. An attachment for flat carriers comprising a stationary barrier, members hinged at the ends of said barrier with key-hole slots at right angles to their axes of movement, clamp bolts having their head ends afforded fulcrum support in the barrier with the threaded ends through the key-hole slots 115
- aforesaid, and complementarily-shaped nuts adapted for passage through said key-hole slots and coaction with the hinged members to secure the latter in active position or support them when inactive. 120
8. An attachment for flat carriers comprising a stationary barrier, members hinged at the ends of said barrier with key-hole slots at right angles to their axes of movement, clamp bolts having their head ends afforded fulcrum support in the barrier with the threaded ends through the key-hole slots aforesaid, complementarily-shaped nuts adapted for passage through said key-hole slots and coaction with the hinged members to secure the latter in active position or support them when inactive, and stops on the hinged members engageable by the nuts to prevent accidental release of the hinged members from the clamp bolts. 130
9. An attachment for flat carriers comprising a stationary barrier including end members secured in spacial relation by paralleling retainers with intervening partitions, members hinged at the ends of said barrier with key-hole slots at right angles to their axes of movement, clamp bolts having their head ends afforded fulcrum support in the barrier partitions and their threaded ends extended through the key-hole slots aforesaid, and complementarily-shaped nuts adapted for passage through said slots and coaction with the hinged members to secure the latter in activity and support them when inactive. 140
10. An attachment for flat carriers comprising a stationary barrier including end members secured in spacial relation by paralleling retainers with medially located intervening partitions, said partitions having elongate vertical apertures therein, members hinged at the ends of the barrier with key-hole slots at right angles to their axes of movement, clamp bolts having their head ends afforded fulcrum support in the partition apertures with the screw-threaded ends extended through the key-hole slots aforesaid, and similarly-shaped nuts adapted for passage through said slots for coaction with the hinged members to secure the latter in active position and support them when inactive. 150
11. An attachment for flat carriers comprising a stationary barrier including end members secured in spacial relation by paralleling retainers with medially located intervening partitions, said partitions having elongate vertical apertures therein, members hinged at the ends of the barrier with key-hole slots at right angles to their axes of movement, clamp bolts having their head ends afforded fulcrum support in the partition apertures with the screw-threaded ends extended through the key-hole slots aforesaid, similarly-shaped nuts adapted for pas-

sage through said slots for coaction with the hinged members to secure the latter in active position and support them when inactive, and stops on the hinged members at the juncture 5 of the cylindrical and slotted portions of the key-hole slots for coaction with the nuts to prevent accidental release of said hinged members.

In testimony whereof, I have hereunto 10 signed my name at Altoona, Pennsylvania, this 4th day of February, 1931.

FREDERICK K. FILDES.
